UNITED STATES PATENT OFFICE.

WILLIAM B. FINK, OF NEW YORK, N. Y.

STATIONARY SIGN CONSTRUCTION.

1,414,350.

Specification of Letters Patent.

Patented May 2, 1922.

Application filed August 22, 1921. Serial No. 494,354.

To all whom it may concern:

Be it known that I, WILLIAM B. FINK, a citizen of the United States, and a resident of New York, in the county of New York and State of New York, have invented certain new and useful Improvements in a Stationary Sign Construction, of which the following is a full, clear, and exact specification.

10 This invention relates more particularly to a class of structures adapted to be used for advertising purposes.

My invention has for its object primarily to provide a sign construction designed to be employed especially in the open in the vicinity of highways and at other conspicuous places for displaying on a surface element advertisements and appropriate subject matters in billboard and poster forms 20 for observation, and which is of a knock-down type combining great durability when erected as well as providing an unusually large area of surface for displaying the matter by reason of enabling both faces of 25 the element to be utilized if desired. The invention also contemplates the provision of a sign construction adapted to permit various subject matters to be provided if preferred on a number of surface elements 30 at a given place and then transported for interchange of use as occasion may require, thereby dispensing with the necessity for repainting each sign separately at its 35 respective locality when it is desired to change the subject matter as is incident to the types of such signs at present in use.

The invention consists essentially of two columns adapted to be supported in stationary upright positions in spaced relation, and 40 adapted to be removably mounted to the columns crosswise between their lower parts is a bar having in its upper edge a lengthwise groove. Adapted to be removably mounted to the columns crosswise between 45 their upper parts are a pair of spaced bars for receiving therebetween as well as between the columns a removable surface element which is also adapted to be removably seated in the groove of the lower bar. This 50 element may consist of a single plate or a plate divided into a number of sections, and on one or both faces of the element may be painted, printed or otherwise provided suitable subject matter for public display.

55 With these and other objects in view, the invention will be hereinafter more fully de-

scribed with reference to the accompanying drawing forming a part of this specification in which similar characters of reference indicate corresponding parts in all the views, 60 and will then be pointed out in the claims at the end of the description.

In the drawings, Figure 1 is a fragmentary view showing an elevation of one form of sign construction embodying my invention.

Fig. 2 is a detail sectional view taken on the line 2—2 of Fig. 1, with the surface element removed therefrom.

Fig. 3 is a detail sectional view taken on the line 3—3 of Fig. 1, also with the surface element removed therefrom.

Fig. 4 is a reduced elevation of a surface element adapted to be used in the sign, and

Fig. 5 is a reduced elevation of another 75 form of surface element which may be employed in the sign.

The sign construction is composed of two columns or posts, as 10 and 11, which may be of any suitable sizes and shapes, though 80 the columns illustrated are substantially square or rectangular in cross section as well as being of lengths so that their lower end parts may be sunken or embedded in an appropriate base, as 12, such as earth in the 85 vicinity of a public highway or other prominent place whereby the other parts of the columns will be in upstanding positions in spaced relation above the base. The columns 10 and 11 may be made of concrete or other 90 cementitious material, or made of a suitable composition or of metal. In the lower parts of the columns 10 and 11 are openings, as 13 and 14, which are in register, and in the upper parts of the columns are two other 95 registered openings, as 15 and 16, which are on vertical alinement with the openings 13 and 14.

In the lower openings 13 and 14 of the columns are adapted to be removably 100 mounted the ends of a bar or member 17, and this bar may be of a size to fit snugly in the openings with its ends terminating at the opposite lateral faces of the columns when positioned in the base or support 12. 105 In the upper edge of the bar or member 17 is a groove 18 extending lengthwise of the bar, and this groove is of a length so that its ends terminate at the columns. To releasably fasten the grooved bar or member 110 to the columns on the ends of the bar may be protruding lugs 19, 20, and on these

lugs may be washers 21, 22 and nuts 23, 24 adapted to be screwed on the lugs for releasably tightening the bars in the columns.

In the openings 15 and 16 of the columns 5 10 and 11 are adapted to be removably mounted two spaced bars 25 and 26. The central parts of these bars are spaced at a distance corresponding to the width of the groove 18 of the bar 17, and these bars are 10 arranged so that the space 26^a therebetween is also in register with the groove 18. The ends of both of the bars 25 and 26 are enlarged in angular shapes, as at 27 and 28, and these enlarged ends are of sizes so that 15 they fit in close contact as well as closely fitting removably in the openings 15 and 16 of the columns 10 and 11. The bars and these enlarged ends are of lengths so that the ends terminate at the opposite lateral 20 faces of the columns 10 and 11, and projecting beyond the columns from each pair of the ends are contacting lugs 28^a and 28^b substantially semi-circular shapes which are exteriorly threaded. On these pairs of lugs 25 may be washers 29, 30 and nuts 31, 32 adapted to be screwed into engagement with the washers to move the washers into contact 25 with the columns for releasably fastening the spaced bars to the columns.

30 In the space 26^a of the bars 25, 26, and in the groove 18 of the bar 17 between the columns 10 and 11 are adapted to be removably inserted a surface element, as 33. This surface element may be in the form of a single 35 sheet of metal, or a plate of board or other suitable material, or the element may consist of a number of sections, as 34, 35, 36, Fig. 5. On one or both faces of the surface may be painted, printed or otherwise provided one 40 or more advertisements, as 37, or other appropriate subject matter for display to the public. By providing for the use of both faces of the surface element an area of space may be employed equal to the area of two 45 signs of a like size of the types of signs in ordinary use. Also by providing for the removably use of the surface elements either in a single sheet form or in sections the subject matters may be provided thereon at a 50 convenient place for being transported so that they may be interchangeably applied to the bars 17, 25, 26, as above explained.

55 In the foregoing description, I have embodied the preferred form of my invention, but I do not wish to be understood as limiting myself thereto, as I am aware that modifications may be made therein without departing from the principle or sacrificing any of the advantages of this invention, 60 therefore, I reserve to myself the right to make such changes as fairly fall within the scope thereof.

Having thus described my invention, I claim as new and desire to secure by Letters Patent:—

1. A sign construction, comprising two columns supported in stationary upright positions in spaced relation and the columns having in their lower parts a removable bar disposed crosswise between the columns and 70 the bar having a groove in its upper lengthwise edge, two bars removably disposed in spaced parallel relation between the upper parts of the columns so that the space therebetween is in register with the groove of the 75 lower bar, means on the ends of the grooved lower bar for releasably fastening the bar to the columns, means on the ends of the pair of bars for releasably locking the bars together and for detachably fastening the 80 bars to the columns, and a surface element removably mounted in the space and in the groove of said bars between the columns.

2. A sign construction, comprising two columns adapted to be supported in stationary upright positions in spaced relation and the columns having in their lower parts registered openings as well as having registered openings in their upper parts, a bar adapted to be removably disposed in the lower 85 registered openings crosswise between the columns and the bar having a groove in its upper lengthwise edge, two bars adapted to be removably disposed in spaced parallel relation in the upper registered openings 90 crosswise between the columns so that the space therebetween is in register with the groove of the lower bar, and a surface element adapted to be removably mounted in the space and in the groove of said bars between the columns. 95

3. A sign construction, comprising two columns adapted to be supported in stationary upright positions in spaced relation and the columns having in their lower parts registered openings as well as having registered 105 openings in their upper parts, a bar adapted to be removably disposed in the lower registered openings crosswise between the columns and the bar having a groove in its 110 upper lengthwise edge, two bars adapted to be removably disposed in spaced relation in the upper registered openings crosswise between the columns so that the space therebetween is in register with the groove of the lower bar, means on the ends of the grooved 115 lower bar for releasably fastening the bar to the columns, means on the ends of the pair of bars for releasably locking the bars together and for detachably fastening the bars 120 to the columns, and a surface element adapted to be removably mounted in the space and in the groove of said bars between the columns.

This specification signed and witnessed this 20 day of August A. D. 1921.
